(57) **CLAIM**

The ornamental design for an adjustable shower brush, as shown and described.

DESCRIPTION

FIG. 1 is a front, left side and bottom perspective view of an adjustable shower brush, showing my new design; FIG. 2 is a rear, right side and top perspective view thereof; FIG. 3 is a top plan view thereof; FIG. 4 is a bottom plan view thereof; FIG. 5 is a front elevation view thereof; FIG. 6 is a rear elevation view thereof; FIG. 7 is a right side elevation view thereof; FIG. 8 is a left side elevation view thereof; FIG. 9 is a front, left side and bottom perspective view of the adjustable shower brush shown in FIGS. 1-8, but where the adjustable shower brush is shown in a folded configuration; FIG. 10 is rear, right side and top perspective view thereof; FIG. 11 is a top plan view thereof; FIG. 12 is a bottom plan view thereof; FIG. 13 is a front elevation view thereof; FIG. 14 is a rear elevation view thereof; FIG. 15 is a right side elevation view thereof; and, FIG. 16 is a left side elevation view thereof.

The broken lines in the figures illustrate portions of the adjustable shower brush that form no part of the claimed design.
